UNITED STATES PATENT OFFICE

2,298,904

ELECTRIC DISCHARGE APPARATUS

William J. Scott and Leonard J. Davies, Rugby,
England, assignors to General Electric Company,
a corporation of New York

Application October 1, 1940, Serial No. 359,254
In Great Britain March 19, 1940

4 Claims. (Cl. 176—124)

Our invention relates to electric discharge apparatus including a discharge device having spaced electrodes at least one of which is arranged to be directly heated by the passage of current therethrough for initially raising its temperature. With the common circuit arrangement wherein the operating current for the device is supplied to such an electrode by a connection with one terminal only thereof it has been found that because of the resistance of the electrode there has been an objectionably unequal distribution of the operating current therein so that substantially only that half of the electrode adjacent said connecting terminal is effective as a cathode. It is the object of our invention to provide an improved arrangement by which this objection is avoided.

Our invention will be better understood from the following description taken in connection with the accompanying drawing and its scope will be pointed out in the appended claims.

Referring to the drawing, Fig. 1 is a circuit diagram of one embodiment of our invention and Fig. 2 shows a detail of the thermal switch employed therein.

In Fig. 1, we have represented the electric discharge device by way of example as a well-known form of discharge lamp of the positive column type. As shown the device comprises the envelope 1 having therein the spaced filamentary electrodes 2, each electrode being attached at its ends to the electrode supporting terminal leads 3 and 4. The envelope may contain a suitable gas or vapor, such as mercury, and the inside surface may, if desired, be coated with a suitable phosphor or produce fluorescence. One end of each electrode connects with the source 5 of alternating current which, for example, may be a 115 volt, 60 cycle lighting circuit. One of these connections is shown including the control switch 6 and the other connection is shown including the ballast reactor 7. For the purpose of initially raising the temperature of the electrodes to a point of electron emission the other ends of the electrodes are connected together through the starting switch 8. This switch may, if desired, be a hand operated switch but preferably is operated automatically with a time delay such that it is not opened until the electrodes have reached an electron emitting temperature. During the normal running of the lamp the switch 8 will of course remain open.

With the lamp so connected to the source of current supply those portions of the electrodes which are nearest to the connections leading to

the source are effective as cathodes whereas the portions remote from those connections or near the other ends are substantially ineffective as such. In order to produce a better distribution of operating current supply to the electrodes, we have provided the temperature responsive switch 9 which in its closed position serves to short circuit the electrode with which it is associated. This switch which preferably is arranged within the envelope may, for example, comprise a bimetallic element shown in greater detail by Fig. 2 where it is represented as having one end secured to the electrode supporting terminal 4 and the other end adapted to make contact with the other electrode supporting terminal 3. When the lamp is cool the bimetallic switch is in open circuit position. When the lamp is in operation, however, the heat received by the switch from the discharge and from the adjacent electrode is sufficient to warp the switch to its closed circuit position whereby current is supplied to the electrode from both ends instead of at one end as heretofore. Thus, the entire electrode becomes electron emissive during the normal operation of the lamp and the objectionable inequality in the distribution of the operating current is avoided.

While we have described our invention as applied to a lamp for operation from a source of alternating current supply it will be understood that it may also be operated from a source of direct current supply in which case only that electrode which is cathode need be provided with a short circuit switch. It will of course be understood that where the lamp is operated on direct current a resistive ballast would be employed instead of a reactive ballast as shown.

What we claim as new and desire to secure by Letters Patent of the United States is:

- 40 1. In combination, an electric discharge device having spaced electrodes, one of which has an appreciable amount of resistance, means for connecting said electrodes with a source of current supply to energize the device and initially to heat said one electrode by the passage of heating current therethrough, and means responsive to heat produced by said device for short-circuiting said one electrode.
- 45 2. In combination, an electric discharge device having spaced electrodes, one of said electrodes having a filamentary form, means for connecting said electrodes with a source of current supply to energize the device and initially to heat said electrode by the passage of current therethrough, and a thermal switch responsive to heat pro-

duced by the device for shunting said filamentary electrode.

3. In combination, an electric discharge device having spaced electrodes comprising an enclosing envelope having spaced filamentary electrodes therein arranged to be initially heated by passing a current therethrough, each of said electrodes having terminal leads secured in said envelope and a thermal switch associated with each electrode and arranged within the envelope for electrically connecting together the leads of each electrode.

4. In combination, an electric discharge device

having spaced electrodes comprising an enclosing envelope having spaced filamentary electrodes therein arranged to be initially heated by passing a current therethrough, each of said electrodes having terminal leads secured in said envelope and a bimetallic switch secured at one end to one terminal lead of each electrode and arranged in response to a predetermined rise in temperature to electrically engage the other terminal lead of that electrode.
